FRITZ STOLZENBERG, OF SHELTON, CONNECTICUT, ASSIGNOR TO SIDNEY BLUMEN-
THAL & COMPANY, INC., OF NEW YORK, N. Y., A CORPORATION OF NEW YORK.

IMITATION FUR AND METHOD OF PRODUCING THE SAME.

Application filed August 28, 1924. Serial No. 734,745.

To all whom it may concern:

Be it known that I, FRITZ STOLZENBERG, a citizen of the United States, and resident of Shelton, in the county of Fairfield and State 5 of Connecticut, have invented a new and useful Improvement in Imitation Fur and Methods of Producing the Same, of which the following is a specification.

This invention relates to imitation fur 10 and the method of producing the same, and has for an object to provide an article which is an imitation of a plurality of fur pelts secured together.

Another object is to provide such an article 15 which is actually formed in a continuous sheet and yet gives the appearance of a number of separate skins or pelts.

A further object is to provide such an article which includes suitable marking in 20 imitation of the characteristic marking of the animal the fur of which it is intended to represent.

Another object consists in providing such an article which imitates the well known 25 fur blankets or large sections of pelts sewed together, which fur blankets are commonly merchandized for the manufacturing of fur garments.

Another object consists in providing a 30 novel method of producing an article having the above named characteristics, with the fur hairs firmly embodied in the back but independently projecting therefrom as animal hairs from the skin.

A further object consists in providing certain improvements in the material, arrangement and steps followed in the method, whereby the above named and other objects 35 may effectively be attained.

A practical embodiment of my invention 40 is represented in the accompanying drawings, in which—

Fig. 1 represents a plan view of a section of material made according to the invention and,

Fig. 2 represents a transverse section, on an enlarged scale, of the same.

As is well known, many of the handsomest fur garments are composed of a considerable number of animal pelts which are appropriately arranged according to their marking and other characteristics, and sewed together in order to give a very beautiful effect to the garment, which is due largely to the arrangement of the individual pelts

with respect to each other. This custom is also followed in manufacturing the well known fur blankets which blankets are provided by the manufacturer to the furrier or garment manufacturer to be employed in 60 the production of the latter's garments.

My invention contemplates an imitation of such garments and blankets which can be made in a continuous piece and which is, of course, very much cheaper than the actual 65 fur articles, while yet partaking of many of the attractive characteristics of the genuine article.

In carrying out my invention, I have a suitable pile fabric woven in the customary 70 manner. This pile fabric may have, for instance, a cotton base or back, and the pile may, for instance, be composed of fiber silk such as that which is commonly called Rayon.

Care should be taken to select fiber for the pile which is adapted to imitate the outstanding characteristics of the fur being copied, and particular care should be exercised in predetermining the length and thickness, or density, of the pile for this reason.

After the materials have been selected and the fabric woven, a number of designs representing the characteristic markings of the animal the fur of which is being imitated are printed directly upon the pile, and care should be taken to arrange these designs in a somewhat artistic and attractive manner in line with the skill and taste commonly employed by the manufacturer of 90 fur blankets or garments.

I have found that a convenient way of printing these designs on the pile fabric is to have suitable wooden blocks, rollers or the like manufactured and to print with ink 95 on the pile by use of the said blocks, rollers or the like. It will be evident however, that other methods of printing may be employed without departing from the spirit of my invention.

After the designs have been imparted to the pile, it is laid on a surface and then subjected to treatment by a whirring process for the purpose of producing certain lines of demarcation between the various printed designs, which lines are established by interrupting or disturbing the smooth continuous lay and sheen characteristic of the pile.

This whirring process as applied in carry-

ing out my invention may consist in taking the whirring device or tool, which includes a rotating element, and manually applying this rotating element directly to the pile, 5 moving the same, as it rotates, along between the various designs printed on the piece. This operation serves to depress the pile in certain places and also to change its lay or slant so that the various threads 10 composing the pile along certain lines will be more erect than their neighbors or will slant in a direction different from the slant or lay of their neighbors.

The result of the whirring treatment is 15 thus to make an impression on the pile, intermediate the various designs, that closely resembles the appearance resulting from sewing the edges of a number of animal pelts together.

20 This whirring treatment also gives a wavy appearance to the pile and, by interrupting the slant of its lay, varies the effect produced upon the eye in regard to the sheen, so that the result is very beautiful.

25 After the whirring process is finished the article is completed and may be sold as a fur blanket or directly employed in the manufacture of garments, as desired.

In the accompanying drawing, the base or 30 back is denoted by 1; the pile in general by 2; the designs printed thereon by 3; and the marking formed by the whirring process, by 4. It will be noted, in the present instance, the marking is calculated to imitate 35 that of a chipmunk.

While I have, for the purpose of clearness, recited, in the above description, certain specific materials and a certain specific design, as well as a certain method of printing the design on the material, it will be 40 realized that the invention may also be carried out by changing all these features, and I therefore desire it to be understood that various changes may be resorted to in the

material, arrangement, design, and steps 45 followed in carrying out the method, without departing from the spirit and scope of my invention; and that I do not intend to be limited to the details herein shown and described, except as they are included in 50 the claims.

What I claim is:—

1. A method of producing an imitation of a fur blanket composed of a plurality of pelts sewed together, which includes the 55 following steps, providing a pile fabric; imparting a plurality of designs to the pile; and disturbing the pile intermediate the designs by applying a whirring instrument thereto.

2. A method of producing an imitation of a fur blanket composed of a plurality of pelts sewed together, which includes the following steps, providing a pile fabric; imparting a plurality of designs to the pile; 65 and disturbing the pile intermediate the designs by manually applying a whirring instrument thereto.

3. A method of producing an imitation of a fur blanket composed of a plurality of 70 pelts sewed together, which includes the following steps, providing a pile fabric; printing a plurality of designs on the pile; and disturbing the pile intermediate the designs by applying a whirring instrument 75 thereto.

4. A method of producing an imitation of a fur blanket composed of a plurality of pelts sewed together, which includes the following steps, providing a pile fabric; 80 printing a plurality of designs on the pile; and disturbing the pile intermediate the designs by manually applying a whirring instrument thereto.

In testimony, that I claim the foregoing 85 as my invention, I have signed my name this 14th day of August, 1924.

FRITZ STOLZENBERG.
